LIFE PRESERVER INFLATING DEVICE

Gerald A. Elikann, New York, N. Y.

Application September 10, 1951, Serial No. 245,918

4 Claims. (Cl. 222—5)

1

This invention relates to a device which may be used advantageously in combination with an inflatable article for inflating the article automatically when it is immersed in a body of water.

The present device is applicable to inflatable articles such as life preservers, jackets, vests, rafts and others capable of being buoyed when inflated.

An object of the present invention is the provision of an inflating device attached to an inflatable life preserver of the "Mae West" type for instance, which may be worn by a person, and which device will automatically inflate the preserver and render it buoyant when, through accident or by deliberate action, such person becomes immersed in a body of water, to the end that the person will be saved from drowning.

A further object of this invention is the provision of a device of the indicated character embodying float operated means which is operable for initiating the inflation with the device disposed right side up or upside down.

A further object of the invention is the provision of a device of the character mentioned which is simple, practical, compact and light in weight.

With the foregoing, other objects and advantages of the invention will appear when the following specification is read in conjunction with the accompanying drawings, in which

Fig. 1 is a front view of an inflatable life preserver selected to illustrate the device of the present invention shown applied thereto.

Fig. 2 is a vertical sectional view through the inflating device.

Fig. 3 is a sectional view taken on the line 3—3 of Fig. 2.

Fig. 4 is a fragmentary sectional view showing certain features on an enlarged scale.

In Fig. 1 there is shown an inflatable life preserver in the form of a vest 10 of standard construction now on the market. Such vest generally stated consists of rubberized fabric and has an inlet nipple 11 at one side near the lower end, and a suitable harness 12 for securing the vest on the person using the same.

Also there is shown a commercial container or cartridge 13 which is charged with compressed gas consisting of carbon dioxide. The container is sealed by a puncturable disk 14.

In accordance with the present invention there is provided an inflating device which is secured to the vest 10 and utilizes the cartridge 13 in connection with the inlet nipple 11. The device includes a casing or housing 15 having a com-

partment 16 and a chamber 17 at one side of the compartment 16 and projecting upwardly therefrom. The compartment has a nipple 18 at the bottom at one side, and an internally screw threaded neck 19 on the top, offset with respect to the nipple 18. An inflator cylinder 20 has its upper open end internally threaded and its lower open end externally threaded. The cartridge 13 loosely fits within the cylinder so as to provide clearance for the flow of the gas when liberated from the cartridge. An internally threaded cup 21 is screwed on the lower end of the cylinder 20. The cup 21 cooperates with a bushing 25 to retain the cartridge 13 in a functioning position and may be removed to replace the cartridge. The nipple 18 is screwed into the upper end of the cylinder. The screw connections of the parts will be fluid tight. The cylinder 20 has an outlet port 22 communicating with a cap nut 23 brazed to the cylinder. This nut 23 is screwed on the nipple 11 to establish communication between the interior of the cylinder 20 and the interior of the related inflatable compartment of the vest. A puncturing element 24 has guided axial movement in the bushing 25 screwed into the upper end of the cylinder 20. The pointed lower end of the element 24 rests lightly on the disk 14 in puncturable relation thereto. The upper end of the element 24 projects upwardly through a hole 26 in the bottom of the compartment 16. A gasket secured to the bottom of the compartment 16 surrounds the upper end portion of the element 24 to prevent the escape of gas. A flange 27 encircling the element 24 prevents the element 24 from becoming separated from the cylinder 20. Within the compartment 16 is a hammer 28 which is mounted on an arbor 29 for pivotal movement with respect to the puncturing element 24. A coil spring 30 is arranged on the arbor 29 and has one end engaged with the hammer 28, and its other end bears on the housing 15. The spring 30 serves as the power means for the hammer 28. There are serrations or teeth 31 on the hammer for a purpose to appear. In order to hold the hammer 28 cocked, there is provided a latch member 32 having a reduced upper end portion 33, a flange 34 intermediate the ends of the member, and serrations or teeth 35 on the bottom face of the lower end of the member 32. The teeth 31 and 35 cooperate or intermesh to retain the hammer 28 cocked. A bushing 36 is screwed into the neck 19. The latch member 32 has guided up and down movement in the bushing 36 and is under the influence of a helical spring 37 which surrounds the

latch member 32 between the flange 34 and the pushing 36 in contact therewith. The end portion 33 projects upwardly through a plate 38, the latter having a hole therein for that purpose. The spring 37 constitutes resilient means for moving the latch member 32 into a releasing position in which the teeth 35 are disengaged from the teeth 31, thereby enabling the hammer 28 to strike the puncturing element 24 so it will penetrate the disk 14. The end portion 33 has a concave seat 40.

A trip or trigger arm 41 is pivoted as at 42 to a guard 43 on the inside thereof, and said guard integral with the plate 38 is secured to the housing 15. The arm 41 has a projection 44 with a rounded end which cooperates with the concaved seat 40 to hold the latch member 32 in a latching position with the teeth 35 intermeshed with the teeth 31 on the hammer 28, thereby holding the hammer cocked.

A hollow metal or other kind of float 45 is arranged for up and down movement in the chamber 17. A slot 46 in the float receives one end of the arm 41, there being a certain amount of play between the float and the arm when the float is in its neutral position. Screens 47 secured to the housing at opposite ends of the chamber 17 admit water into the chamber and keep foreign particles out of the chamber. Light helical springs 48 are secured to the opposite ends of the float respectively and bear on the screens 47. The springs 48 yieldingly retain the float in a neutral functioning position.

It will be understood that the float 45 will operate the inflating device when it is right side up or upside down by reason of the arrangement and operation of the parts.

When a person using the vest equipped as shown and described, is immersed in a body of water, the float 45 will be buoyed relatively to the arm 41 by pressure of the water in the chamber 17 causing the pivotal movement of the arm, thereby instantly releasing the latch member 32 from engagement with the hammer 28 by the action of the spring 37. As a consequence the hammer 28 will strike a blow on the puncturing element 24 causing the latter to penetrate or puncture the disk 14, thereby unsealing the cartridge 13 and so liberating the compressed gas. The gas flows in the cylinder 20 through port 22 and inlet nipple 11 into the interior of the vest thereby inflating the vest for the obvious purpose of sustaining the person afloat.

While the inflating device has been shown and described as applied to an inflatable life vest, it is to be understood that the device may be applied to any other inflatable article to be used in an emergency; and that details of the invention may be modified and rearranged in accordance with the scope of the claims.

I claim:

1. An inflating device comprising a housing embodying a chamber having water inlet openings, a float arranged in said chamber to be buoyed by water entering said chamber, a sealed container of inflating fluid under pressure connected with said housing, a spring actuated latch member on the housing, a pivoted spring actuated hammer in the housing, cooperative means on said

latch member and hammer by which the hammer is held cocked by said latch member when the latter is in the latching position, a puncturing element having guided movement on said housing, and a trip on said housing which normally bears on one end of the latch member and thus holds the latch member in its latching position, said trip being positioned to be operated by said float when the latter is buoyed as aforesaid, to perform the following function, namely, to release the latch member to disengage said cooperative means so as to unlatch the hammer enabling the latter to cause the puncturing element to puncture said container, thereby liberating the fluid therein for the purpose of inflating an article connected with the device.

2. An inflating device comprising a housing, a pivoted spring actuated hammer carried by the housing, a sealed container of inflating fluid under pressure, means having a fluid outlet and said means being connected with the housing to support the container within the same, a spring actuated latch member carried by the housing, cooperative means on said latch member and hammer by which the latch member releasably retains said hammer cocked, a puncturing element having guided movement in said housing, and float operated means carried by said housing which cooperates with said latch member which controls the operation of the latter, the provision and arrangement being such that the operation of the float operated means releases the latch member to disengage said cooperative means enabling the hammer to operate the puncturing element so that the latter punctures the container, thereby liberating the fluid for the purpose of inflating an article to which the device may be attached.

3. An inflating device comprising a housing providing a chamber, said housing having water inlet openings communicating with said chamber at the opposite ends thereof, a float arranged in said chamber to be buoyed by water entering said chamber through said openings, a sealed container of inflating fluid under pressure connected with the housing, means arranged in said housing operable to unseal the container to liberate the fluid therein for the purpose of inflating an article, a spring loaded latch in the housing to keep said unsealing means dormant and operable to release said means for the unsealing operation, and a trigger in said housing, said trigger having an arm, said float having a slot into which said arm projects, to release the unsealing means for the aforesaid purpose upon operation of the trigger by the float buoyed in the stated manner.

4. An inflating device as set forth in claim 3, wherein said slot is in one side of the float, and said arm of the trigger projects laterally into said slot.
